UNITED STATES PATENT OFFICE.

FERDIENAND SCHUEDDIG, OF ST. LOUIS, MISSOURI.

SANDSTONE-CRANDALL.

SPECIFICATION forming part of Letters Patent No. 298,417, dated May 13, 1884.

Application filed March 27, 1884. (No model.)

To all whom it may concern:

Be it known that I, FERDIENAND SCHUEDDIG, a citizen of the United States, residing at St. Louis, in the State of Missouri, have invented a new and useful Sandstone-Crandall, of which the following is a specification.

My invention relates to that class of stone-dressing tools specially used for dressing sandstone, in which double-headed points are held in a handle, so as to be readily removed and replaced for sharpening, &c.

My improvements consist in the new and novel manner of holding said tools firmly within the handle.

15 To more fully describe my invention and to better make it understood to others, reference is had to the accompanying drawings, in which—

Figure 1 is a perspective view of my improved "crandall." Fig. 2 is a sectional view of the same. Fig. 3 is a perspective view of the clamp-blocks.

A is the handle, having its forward end slotted, as ordinary, at a.

25 B are the double-headed points, which enter into and pass through the slot of the handle.

C and C' are movable clamp-blocks, one placed in each end of the slot a. These blocks have a notch or open slot, c, to allow their engagement around the flattened sides of the handle at the ends of the slot, thereby being prevented from slipping out of said slot.

30 c' is a long face, which acts against the side 35 of the end tools or points, B.

D is a set-screw at the end of the handle, which acts against the upper block, C', which latter, in turn, presses and clamps the points or tools together, holding them firm from slipping by being pressed against the lower 40 block, C.

The usual manner of holding the points or tools is by means of a wedge or key driven between the end point or tool and one end of the slot, thereby only imperfectly securing the 45 said points from slipping; further, allowing only one end of the points to be used, and necessitating the reversing of the key or either the points in the slot when the other ends of said points are desired to be used.

50 By my improvement in the manner of holding the points, either end may be used with absolute safety, thereby doubly increasing the advantages in the use of the tool, also making it of better advantage to the operator by 55 avoiding the possibility of using the wrong end of the points.

Having thus fully described the construction and operation of my invention, what I claim is—

60 In a crandall, the handle A, having slot a, the points B, blocks C and C', having notches or open slots c and long faces c', and the set-screw D, all combined, constructed, and arranged to operate as and for the purpose set 65 forth.

FERDIENAND SCHUEDDIG.
